UNITED STATES PATENT OFFICE

EDMUND W. MOORE, OF ROCHESTER, NEW YORK, ASSIGNOR TO GENERAL RAILWAY SIGNAL COMPANY, OF ROCHESTER, NEW YORK

LIGHT SIGNAL

Application filed November 5, 1927. Serial No. 231,292.

This invention relates in general to light signals, and has more particular reference to such signals which continue to give distinctive indications upon failures which would normally result in dark indications.

In light signals, such as is particularly used in railway signalling, it is very important, in avoiding danger, to prevent failures of such signals since, when such failures result in dark signals, conditions are not so completely safeguarded as when the light signal is arranged to nevertheless continue its active indication.

With the above and other objects in view it is proposed, in accordance with this invention, to provide a light signal which includes, in combination with a doublet lens combination of lenses, a single incandescent bulb containing a main filament and a reserve filament, whereby both filaments can be readily positioned close to the inner lens of the doublet combination as is necessary, in such lens systems, for being on focus. The single bulb is carried in a socket mounted on an adjustable bracket and provided with sighting means for determining when the lamp is properly positioned.

Means, controlled in accordance with traffic conditions, is arranged to momentarily energize both of the filaments, together with means for immediately or shortly thereafter de-energizing the reserve filament while continuing the energization of the main filament, and to operate, upon breakage or burning out of the main filament, to cut the reserve filament into energization. The main filament is placed on focus, whereas the reserve filament is positioned off focus and above thereof, whereby to give a somewhat diminished, and also slightly depressed, beam sufficient for being picked up and recognized by the engineman as the distinctive signal indication, but of such a character as to advise him, and place him on his notice, that the signal requires attention.

Further objects, purposes and characteristic features of the present invention will appear as the description progresses, reference being had to the accompanying drawing showing, solely by way of illustration,

and without in any limiting sense whatsoever, one form which the invention may assume.

In the drawing:

Fig. 1 is a side elevational section, with parts shown in elevation, of the invention.

Fig. 2 is a fragmentary diagrammatic view showing the circuit arrangements employed.

Referring to the drawing, and first to Fig. 1, there is shown a light signal casing 1, having a removable rear door 2, and a large opening 3 in the front of the casing within which is positioned a doublet lens combination comprising lenses 4 and 5, there being a sunshade or visor 6 fastened to the casing.

Carried by a retaining ring 7 for the inner lens 5, is an adjusting bracket B_R carrying a lamp base receiving socket 8, in which is received an incandescent lamp 9.

The bracket B_R can be adjusted to move the socket 8 in three planes substantially at right angles to each other, whereby to position the lamp 9 at the desired point in the casing relative to the doublet lens, and for a detailed description of this adjusting bracket reference should be had to co-pending application S. N. 131,466 filed August 25, 1926, now Patent No. 1,822,105.

Also carried by the retaining ring 7, is a sighting device S, for determining when the lamp is properly adjusted, and for a detailed description of the construction and operation of this device S, reference should be had to co-pending application S. N. 131,467, filed August 25, 1926, now Patent No. 1,794,586.

Positioned within the bulb of lamp 9 are two filaments 10 and 11, which are respectively main and reserve filaments, the filament 10 when properly positioned being on focus, while the filament 11 is off of focus and above thereof.

As shown in Fig. 2, the light signal is controlled in accordance with traffic conditions, as for example, by means of a track relay TR, connected across track rails 30, to in turn control a line relay L which in turn controls the energization of the lamp filaments.

For automatically maintaining the reserve

filament 11 de-energized, while the main filament is energized when conditions correspond to energization of the signal exist, is a light-out relay CR. The energy for energizing the light signal is derived from the secondary of a transformer T, the primary of which is fed from any suitable desired source of electrical energy.

As shown in Fig. 2, traffic conditions correspond to the energization of the light signal. With relay TR energized, its finger 31 is attracted, to thereby energize relay L, through a circuit obvious from the drawing.

With relay L energized, and its contact finger 12 in attracted position, energy from the secondary of transformer T momentarily energizes both of the filaments 10 and 11 through circuits including; secondary of transformer T, contact finger 12 and front point of relay L, wire 13, and then, in multiple; first through filament 10, wire 14, and relay CR to the common point 15, and, second, through reserve filament 11, wire 16, reactance 17 (which is chosen to equal the reactance of relay CR), wire 18, and contact finger and back point 19 of relay CR to the common point 15; and thence, by wire 20, back to the secondary of transformer T. Light-out relay CR is arranged to pick up on energization to thus break the above traced energizing circuit for reserve filament 11 at its contact finger 19, without affecting the energization of main filament 10.

Let us now assume that the main filament 10 burns out, is broken, or due to any other cause breaks the circuits passing through relay CR. On de-energization of relay CR, its contact finger 19 assumes retracted position, to energize reserve filament 11 through its energizing circuit as described just above with regard to the momentary energization of reserve filament 11 on initial energization of the light signal.

This reserve filament, as shown, and as explained above, is off focus, and above focus, whereby to give a weaker beam than that of the main filament, and to direct this weaker beam slightly downwardly from the direction of the beam from the main filament. In certain conditions it has been found desirable to arrange the reserve filament to give a beam of 60 per cent of the intensity of that of the main filament, and to position it so that its beam will be projected in a direction depressed from the main beam from 2° to 3° . In all events, the reserve filament 11 is so positioned that its projected beam, while being weaker than the main beam, and depressed downwardly therefrom, will still be sufficient for the engineman to readily pick up the light signal indication, while at the same time being advised by the different characteristics of this indication from the usual indication, that something is wrong with the light signal, and that inspection and repair be

given to rectify conditions.

It should be borne in mind, that in order to readily, or in fact, possibly, place the two filaments, main and reserve, in the desired relative position one to the other, they should both be placed in a single incandescent bulb rather than in two separate lamp bulbs.

Furthermore, it is most important, in order to utilize a large solid angle of the total light flux emitted that a doublet lens combination be used. It is well known by those skilled in this art that the focal point of a doublet lens combination lies nearer to the inner surface of the inner lens of the combination, than does the focal point of either of the two component lenses making up the combination, whereby a larger solid angle of light flux can be availed of, than without such a doublet combination. With such a combination, however, of lenses, it would be difficult, or perhaps impossible, to place the two filaments in question close enough to the inner surface of the inner lens if the filaments were placed in separate lamp bulbs. It therefore appears quite obvious that the characteristics of the doublet lens combination used, and of the two filaments in a single lamp bulb, mutually cooperate with each other to permit their needful combinative combination.

It is, of course, wholly within the purview of this invention, to employ the double filament lamp and its automatic control means, in light signals other than that shown and described above. For example, it can be advantageously used in a light signal of the type which employs a single light source and a movable spectacle carrying several different color glasses, all with a single casing, whereby a single light unit displays several signal indications.

In conclusion, in accordance with this invention, when traffic conditions are such as to cause energization of track relay TR, the two filaments 10 and 11 are momentarily energized, after which, the light-out relay CR will operate to de-energize the reserve filament, providing the main filament is intact, until such time as the main filament fails, whereupon relay CR is de-energized and cuts in the reserve filament 11 to give the desired reserve indication, which is sufficient for the engineman to pick up the indication, and at the same time to advise him, due to the somewhat diminished and depressed beam, that inspection and repair of the light signal is necessary.

The above rather specific description of the invention is given solely by way of illustration, and is not intended in any manner whatsoever, in a limiting sense. Obviously, the invention can assume various different physical forms and is susceptible of numerous modifications, and all such forms and modifications, are intended to be covered

by this application, as come within the appended claims.

Having described my invention, I now claim:

- 5 1. In a light signal for railway signal systems, a casing, a doublet lens system in the front of the casing, a lamp bulb within the casing and projecting into the cup portion of the inner lens, a main filament and a reserve filament in the bulb, and means for 10 automatically causing energization of the reserve filament upon failure of said main filament, the main filament being adjusted on the focus of said lens system, and the 15 reserve filament positioned off, and above, such focus whereby to indicate failure of the main filament by the lessened intensity and the position of the beam produced by the reserve filament. 80
